By his attorney,

Inventor:

Leo Wallenstein,

J. K. Richards.

UNITED STATES PATENT OFFICE.

LEO WALLENSTEIN, OF BROOKLYN, NEW YORK.

STENCIL.

1,413,246.

Specification of Letters Patent. Patented Apr. 18, 1922.

Application filed September 3, 1920. Serial No. 407,924.

To all whom it may concern:

Be it known that I, LEO WALLENSTEIN, a citizen of the United States, residing in Brooklyn, in the county of Kings and State 5 of New York, have invented certain new and useful Improvements in Stencils, of which the following is a specification.

This invention relates to a series of stencils and has for one object to provide suitable stencils for letters or other characters provided with means serving for quickly guiding and positioning a succeeding stencil against and in alinement with a preceding stencil before the latter is displaced.

Another object is to provide means, as for instance, a window for positioning a succeeding stencil relative to and by viewing a preceding character already stenciled after the succeeding stencil is removed, and for permitting the succeeding character to be positioned in or out of alinement with the preceding character, as when stenciling to a curved line.

Still another object is to provide flanges serving as handles and to guide the stencil brush and to prevent the stencil ink or other material from passing into the window or below the lower edge of the stencil plate.

Other objects of the invention will appear as the description proceeds; and while herein minute details of the invention are described, the invention is not limited to these, since many and various changes may be made without departing from the scope of the invention as claimed.

In the accompanying drawing, showing by way of example two of many possible embodiments of the invention,

Fig. 1 is a perspective view of one of the 40 stencil plates;

Fig. 2 is a perspective view of two plates of a modified form, showing the plates assembled in alinement;

Fig. 3 is a plan showing a plate in use for 45 making unaligned characters, and

Fig. 4 is a sectional view showing nested stencil plates of the form of Fig. 2.

My improved stencil comprises a series of stencil sheets one for each letter or character 50 ter, each comprising a flat elongated rectangular sheet of brass 5 having cut therein a stenciled letter or other character 6 in the right hand or forward intermarginal portion of the sheet remotely spaced from the 55 edges thereof. A letter or character-sized rectangular window 7 is cut in the rear or

left-hand intra-marginal portion of the sheet and spaced normal inter-letter distance both from said letter or character 6 and the left hand edge 8 of the sheet. An upstanding 60 flange 9 is turned up from, and extends from end to end of, the right hand edge of said window.

An edge flange 10 is disposed at the lower edge of the plate perpendicular to the plate 65 and has an intermediate off-set whereby the portion 12 to the left is slightly upwardly off-set from the right hand portion 14. Said flanges 9 and 10 serve for quickly positioning a succeeding stencil 15 (Fig. 2) against and 70 in alinement with the preceding stencil 5 before the latter is displaced, by placing the left hand edge 8 of the plate against the upstanding flange 9 or 19 of the preceding stencil, and placing the left hand portion 12 of 75 the edge flange of the succeeding stencil 15 against the upper face of the right hand portion 15 of the edge flange of the preceding stencil 5. The right hand end of each portion 14 is cut away as at 20 to prevent interference with the succeeding stencil (Fig. 2).

Said window 7 serves for positioning a succeeding stencil relative to and by viewing a preceding character 22 (Fig. 3) already stenciled, and assist and permits the succeeding character 23 to be positioned in alinement with, or either above or below the line of, the preceding character, as when stenciling to a curved line, as shown in Fig. 3. Said flanges 9 and 10 also serve as handles, 85 and to guide the stencil brush and to prevent the stencil material from passing into the window or below the lower edge. If desired, the flange 19 (Figs. 2 and 4) may be cut at an angle at its lower edge 25, to permit 90 the easy nesting of the stencil plates, as shown in Fig. 4, for shipping or storing.

The stencil plate may be folded flat upon itself at the edges, as at 26, for strengthening the stencil, and permitting the use of 100 thin plates.

The operation of the stencil is very simple. A stencil is placed in the desired position for the initial letter, using one of the flanges as a handle, and the stencil ink applied. If the method of Fig. 2 is used, the succeeding stencil is then positioned as shown and its forward end held down as the preceding stencil is raised and removed, whereupon the operation is repeated.

If the method of Fig. 3 is used, the operation of the stenciling the first letter is the

same as above described, after which the stencil is removed, and the window of the succeeding stencil is registered with the preceding letter, after which the succeeding letter is stenciled.

I claim as my invention:

1. A series of stencils each comprising a sheet having a stenciled character; and an upstanding lower edge flange at the lower edge of said plate.

2. A series of stencils each comprising a sheet having a stenciled character; and an upstanding lower edge flange at the lower edge of said plate, said flange serving for aligning a succeeding stencil relative to preceding stencil by placing the rear portion of the edge flange of the succeeding stencil against the upper face of the right-forward portion of the edge flange of the preceding stencil.

3. A series of stencils each comprising a sheet having a character; an upstanding flange at the rear edge of said character; and an lower edge flange at the lower edge of said plate.

4. A series of stencils each comprising a sheet having a character; an upstanding flange at the rear edge of said character; and a lower edge flange at the lower edge of said plate, said flanges serving for quickly positioning a succeeding stencil against and in alinement with a preceding stencil by placing the rear edge of the plate against the upstanding flange of the preceding stencil, and placing the rear portion of the edge flange of the succeeding sheet against the upper face of the forward portion of the edge flange of the preceding stencil.

5. A series of stencils each comprising a

sheet having a character; an upstanding flange at the rear edge of said character; and a lower edge flange at the lower edge of said plate; said flanges serving as handles and to guide the stencil brush and to prevent the stencil material from passing into the window or below the lower edge.

6. A series of stencils each comprising a sheet having a stenciled character in one portion of the sheet; a window in another portion of the sheet; an upstanding edge flange at an edge of said plate; and an upstanding flange between said window and said character and substantially perpendicular to said edge flange and having a lower inclined edge to permit nesting with a window of a superposed plate.

7. A series of stencils each comprising a flat elongated rectangular sheet of brass having a stenciled letter or other character remotely spaced from the edges of the sheet in the right hand intermarginal portion of the sheet; a letter- or character-sized rectangular window cut in the left hand marginal portion of the sheet and spaced normal inter-letter space from said letter or character and the left hand edge of the sheet; an upstanding flange turned up from, and extending from end to end of, the right hand edge of said window; and a lower edge flange perpendicular to the plate and having the portion to the left of said upstanding flange slightly upwardly off-set from the right hand portion to the right thereof.

LEO WALLENSTEIN.
